TWO STROKE CYCLE INTERNAL COMBUSTION ENGINE

George L. Strebler, St. Louis, Mo.

Application August 4, 1931, Serial No. 555,036

21 Claims. (Cl. 123—74)

This invention relates to improvements in two stroke cycle internal combustion engines, and, has for its object to increase their efficiency. According to one feature of the invention, each 5 piston has a head at each end; each piston is reciprocal in a one piece cylinder which constitutes a working cylinder at its upper end, and a fuel pumping cylinder at its lower end. A second feature of the invention is in providing each piston with a separable wrist-pin carried intermediate the heads thereof. A third feature of the invention is in connecting each piston with the crank shaft of the engine by means of two connecting rods, the upper ends of each pair 10 of connecting rods being connected with the ends of their respective wrist-pin and the connecting rods being disposed to the outside of each cylinder wall. A fourth feature of the invention is in providing each cylinder with a fuel transfer cylinder of smaller bore than its engine cylinder to serve as a manifold between the pumping cylinder and the working cylinder. A fifth feature resides in providing means for admitting fuel from a carburetor to the pumping cylinder. A sixth feature resides in means for admitting compressed fuel from the pumping cylinder to the transfer cylinder. 15

A seventh feature resides in reciprocating means for boosting a fuel charge from the transfer cylinder through a port in the working cylinder wall and a passage in the piston into the working cylinder. An eighth feature resides in means for admitting crank case air into the pumping cylinder. A ninth feature is in the provision of means for admitting outside atmosphere to the crank case and then into the pumping cylinder at the end of the upstroke of the piston. A tenth feature of the invention resides in providing a cylinder closed at its lower end 20 as respect to the crank case chamber by the employment of a movable head within the lower end of the pumping cylinder so that the area of the pumping cylinder can be varied, as desired. An eleventh feature of the invention resides in the provision of means for raising or lowering the movable head in the lower end of the pumping cylinder. A twelfth feature resides in providing means for oiling the wrist-pin under pressure and in oiling the cylinder wall 25 through the wrist-pin. A thirteenth feature resides in providing each working cylinder with two spark plugs, the plugs firing alternately with the alternate upstrokes of the piston, and, a fourteenth feature resides in the provision of a two stroke cycle internal combustion engine 30

which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended. 5

In order that this invention may be more clearly understood and readily carried into effect, I will now proceed to describe the same with reference to the accompanying drawings, which illustrate embodiments of this invention and wherein like characters of reference designate like parts 10 throughout the several views, and wherein:—

Fig. 1 is a vertical sectional view, partly in side elevation of an engine embodying the features of my invention, the engine shown being a four cylinder of the two stroke cycle type, which is 20 equivalent to an eight cylinder engine of the four stroke cycle type.

Fig. 2 is a vertical sectional view, partly in front elevation, showing one of the engine cylinders and its associated parts, the piston being 25 shown in its upstroke position.

Fig. 3 is a vertical sectional view, partly in front elevation, showing one of the cylinders and its associated parts, the piston being shown in its downstroke position. 30

Fig. 4 is a vertical sectional view, partly in side elevation, showing two of the engine cylinders and associated parts.

Fig. 5 is a front end elevation of the engine shown in part section. 35

Fig. 6 is a rear end elevation of the engine.

Fig. 7 is a top plan view of the engine shown in part section.

Fig. 8 is a detail of a part of the lubricating means shown in part section. 40

Fig. 9 is a vertical sectional view of the modified form of booster piston for the fuel transfer cylinders of the engine.

As will be evident to one skilled in the art, my invention may be adapted to an engine having 45 one, or any number of cylinders. For the purpose of illustration only, I have shown by the drawings an engine having fuel cylinders, which, as is manifest, is equivalent to eight cylinders in a four stroke cycle internal combustion engine. 50 In the drawings, I have designated the four cylinders, generally as A, B, C and D, but in the detailed description of the engine, the engine parts associated with each cylinder has been designated with like characters of reference to avoid prim- 55

ing the reference characters designating parts associated with cylinders B, C and D, as each power unit of the engine is alike in construction, therefore throughout the specification, it will be 5 found that I have used the expression, "each cylinder".

The engine, as constructed from the base up, consists of an engine base, or crank case 1, to which is bolted, or otherwise secured an oil pan 10 2. Formed on the base 1 and depending therefrom are a pair of end main bearings designated 3, and there are intermediate main bearings designated 4 depending from the base 1 directly below and centrally of each engine cylinder.

15 A crank shaft 5 is provided with end journals 6 fitting inside the end main bearings 3 and with intermediate journals 7 fitting inside the intermediate main bearings 4.

20 Formed on the crank shaft 5 on either side of each intermediate journal 7 are connecting rod journals designated 8 on each of which the lower end 9 of a pair of connecting rods 10 for each piston are pivoted, thus providing for double connecting rods to each piston of the engine, as will 25 be more apparent hereinafter, so as to more evenly distribute the strains on the crank shaft 5 and also the wrist-pins over a greater bearing surface. Each pair of connecting rods extend upwardly through slotted openings 11 in the engine base 1 so as to be disposed to the outside 30 of each engine cylinder and the upper ends 12 of each pair of connecting rods are connected to the ends of their respective wrist-pins designated generally, as E.

35 The wrist-pin E for each piston, which pistons are designated generally, as F, and workable in their respective engine cylinder, is separable and consists of two parts designated 13 and 14. The part designated 13 is provided with an inner reduced end extension 15 which is externally screw threaded and receivable in a screw threaded bore 16 at the inner end of the other part designated 14, and when thus assembled, constitutes the 40 wrist-pin which is receivable in a transverse bore 17 intermediate the heads of each piston, with the ends of each wrist-pin projecting beyond opposite sides of the piston and passing through opposed vertical slotted openings 18 in the 45 wall of each cylinder and fitted in the upper ends of the connecting rods.

50 The upper bored bearing ends of each pair of connecting rods are split, as at 19 so as to be clamped to the ends of their respective wrist-pin by means of a fastening device, such for instance 55 as a bolt 20, thus causing the wrist-pin to rock in its piston bearing with the throw of the crank shaft.

56 Each engine cylinder is closed at its upper end by a removable engine head 21, which is held in 60 its fixed position by means of studs 22 carrying the nuts 23. The upper end portions of the cylinders are constructed so as to be provided with water cooling spaces 24, which communicate with a water cooling space 25 in the engine head 21. 65 Water connections being old in engines of the internal combustion type, description and illustrations thereof is believed unnecessary. The engine cylinders are preferably case en-bloc and are suitably secured to the engine base plate 1.

70 The ends of the engine block are cast open below the water cooling spaces 24 and are closed by means of removable cover plates 26 secured in place by means of suitable fastening devices 27. 75 One side of the engine is also provided with a re-

movable cover plate 28 secured in place by means of fastening devices 29.

5 Each cylinder employed in the engine construction and illustrated as A, B, C and D and regardless of the number of cylinders employed, are each preferably of a single inside diameter throughout their entire length, and each cylinder consists of an upper portion constituting a working cylinder 30 and a lower portion constituting a pumping cylinder 31.

10 The piston E for each cylinder consists of an upper portion, or working head 32 fitted with a plurality of suitable rings 33 and a lower portion, or pumping head 34 fitted with a plurality of suitable rings 35. Thus, it will be observed that 15 each piston is a double headed piston workable within a single engine cylinder and owing to the long length of the piston, piston slap is made impossible. The piston for each engine cylinder is preferably hollow, excepting for the wrist-pin 20 bearing 36, and it is internally ribbed, as at 37, to strengthen the same.

25 A suitable head 38 fitted with a plurality of suitable rings 39 is positioned in the lower end of the pumping end of each engine cylinder. Each head 38 is connected with a suitable shaft 40 by means of a connecting rod 41 and a cam 42. The lower end of the connecting rod is mounted on the cam which is fixed to the shaft 40, and the upper end of the connecting rod is pivoted 30 to a pair of ears 43 depending from the lower end of the head 38, by means of a wrist-pin 44.

35 The shaft 40 is journaled in bearings 45 and 46 formed in each of the aforesaid intermediate main bearings 4, and the outer end of the shaft 40 extends beyond one of the side faces of the engine base 1 so that the shaft can be turned to either raise the head 38 through the cam 42 and connecting rod 41 in the pumping cylinder when high compression is desired, or lower the 40 position of the head 38 in the pumping cylinder to lower the compression in the pumping cylinder.

45 Each engine cylinder is formed on one side with a suitable fuel transfer cylinder G of suitable inside diameter within which is workable a suitable fuel booster piston 47 fitted with suitable rings 48 disposed on opposite sides of a peripheral fuel inlet groove 49, which is disposed intermediate the ends of the piston 47. The upper end 50 of the piston 47, which is in the 50 form of an inverted skirt, is provided on its side facing its respective engine cylinder, with a cut-away portion 51 to serve as a fuel inlet passage to the transfer cylinder from the pumping cylinder when in register with the port 52 in the wall 55 of the pumping cylinder and the fuel transfer cylinder, to permit compressed fuel to be forced from the pumping cylinder into the fuel transfer cylinder with the downstroke of the piston in the pumping cylinder. The peripheral fuel inlet groove 49 of the transfer cylinder piston 47, when in register with the fuel inlet port 53 in the wall of the transfer cylinder, also registers with a port 52 and permits fuel from a down draft carburetor, not shown, to pass from an intake manifold 54 into the pumping cylinders during the upstroke of the pistons F working therein. The outlet ends of the intake manifold 54 each feed two pumping cylinders, as will be apparent in Fig. 7.

70 A suitable drive, or crank shaft 55 is suitably journaled within the crank case chamber adjacent the main crank shaft 5, and is timed to travel at the same speed of rotation as the main crank shaft, and the shaft 55 is connected with each 75

- fuel transfer cylinder piston by means of a suitable connecting rod 56. The two crank shafts are connected by means of gears 57 and 58, and an intermediate idler gear 58', or an equivalent driving connection. The crank throw positions of the two crank shafts are disposed at approximately right angles to each other with the crank throws of the crank shaft 40 traveling in advance of the crank throws of the main crank shaft.
10. The wall of each engine cylinder is provided with an inlet port 59 and with an exhaust port 60, which latter port is opposed to inlet port 59, and disposed higher in the cylinder wall with relation to the inlet port. The piston of each engine cylinder is provided in its working head end with an L-shaped inlet port 61 which is adapted to register at its lower end with a port 62 in the wall of each engine cylinder that communicates with the upper end of the fuel transfer cylinder. The exhaust port 60 of each engine cylinder is fully opened when the double headed piston therein is in its lowermost position, as is the fuel intake port, but the opening time of each port is not exactly the same, the exhaust port 20. preferably being opened slightly before the fuel intake port. In both instances, the ports are closed by the sliding movement of the double headed pistons within the engine cylinders, thus no mechanically actuated valves are employed.
25. Two spark plugs designated 63 and 64 are employed with each engine cylinder and are carried in openings in the engine head so as to be disposed at the top of each engine cylinder. These plugs are connected to a suitable ignition system, not shown, having a distributor so arranged as to fire alternately, plug 63 firing to drive the piston down in one stroke, and plug 64 firing to drive the piston down in its next stroke, etc.
- In the modification shown in Fig. 9, the means 40. for reciprocating the fuel transfer cylinder piston comprises a cam 70 fixed to a shaft 71 in lieu of the crank shaft 40 shown in Fig. 3, and also includes a push rod 72 guided in a bearing 73 and a coiled compression spring 74 interposed between the bearing and a head 75 at the lower end of the push rod 72. The lower face of the push rod head 75 is slotted, or recessed, to receive the cam 70 to prevent rotation of the push rod and the piston fixed thereto. The upper end of the push rod 72 is suitably connected with the lower end of the piston 47 which is reciprocable in the fuel transfer cylinder G. Either the preferred, or modified arrangement for reciprocating the piston in the fuel transfer cylinder is practical, but 55. the modified arrangement is probably the cheapest in construction.
- Briefly, the operation of the four cylinder engine illustrated, is as follows:
- During the firing, or down stroke of the piston 60. in engine cylinder A, fuel is compressed, which has been previously received in the pumping end of the cylinder and forced into its respective transfer passage, and the charge in the fuel transfer passage is then boosted into the working end of engine cylinder A immediately following the escape of burnt, or exhaust gases therefrom to be recompressed with the upstroke of the piston, and fired at the end of the upstroke thereof, there being a fresh charge drawn into the pumping end 65. of the cylinder with the upstroke of the piston. The cycle of operation described for cylinder A is the same in all cylinders, and the sequence, or order of firing is determined by the number of cylinders employed and the relative positions of 70. the main crank throws. The crank throws asso-

ciated with the fuel boosting pistons reciprocal in the fuel transfer cylinders are identical in sequence, or order with the main crank shaft throws, but preferably in ninety degree advance order of the crank throws of the main crank shaft. For instance, the four cylinder engine illustrated, preferably has a firing order, as follows: cylinder A being fired first; cylinder B being fired second; cylinder D being fired third and cylinder C being fired fourth, and this order of firing is repeated 10. during the running of the engine.

It is evident, regardless of the number of engine cylinders employed, that the pistons will be moved downward each time as a power stroke and the spark plugs on each cylinder will be fired alternately. It will be here understood that the fuel from the carburetor will be thoroughly intermingled and broken up into a gaseous state due to the fact that it is, in fact, compressed three times before being fired, first in the pumping 20. cylinder position of each engine cylinder, second in the fuel transfer cylinder associated with each engine cylinder, and, third in the working portion of the engine cylinder. It is further evident that the crank case is dry and that the 25. bottom of each cylinder is closed to the crank case. Outside air is admitted through inlets 28 and A' to the pump portion of each engine cylinder and also fumes from the crank case are admitted through the engine base openings 11 and the inlet A' to the pumping cylinders at the end of the upstroke of the pistons in the engine cylinders. The area of the pumping cylinders can be varied and that all bearings, the wrist-pins and the walls of the cylinders are 30. lubricated by a force feed oiling system.

The many advantages of the herein described invention will readily suggest themselves to those skilled in the art to which it appertains.

From the foregoing, it is thought the construction of my engine will be clearly understood and it will be readily appreciated that I have provided an efficient and substantial engine of the class described, and that while the specification manifests, in detail, the construction of the 40. engine, I do not wish to be understood as having limited myself to the specific details of construction and arrangement of parts as herein described and illustrated, as it is manifest that variations and modifications may be resorted to 45. in the features of construction and arrangement of parts in the adaptation of the engine to various conditions of use without departing from the spirit and scope of the invention. I therefore, reserve the right to all such variations, modifications as properly fall within the scope of my 50. invention, as hereinafter claimed.

What I claim is:

1. In an internal combustion engine, an engine cylinder, a double headed piston reciprocally mounted in the cylinder, end closures for the engine cylinder, one of the end closures being removably fixed on the engine cylinder, firing means carried by said removable end closure and the other end closure being carried within the engine cylinder and adjustable longitudinally thereof to vary the compression space between the adjustable end closure and one head of the piston, means providing a metallic path to receive the initially compressed exploded mixture 60. from the compression space at one end of the engine cylinder to be delivered to the recompressing and explosive end of the cylinder, a reciprocal member in said path for boosting the initially compressed explosive mixture into the re- 65.

compression and explosive end of the engine cylinder from said path, an inlet port for one end of the engine cylinder, an exhaust port for said end of the cylinder, said ports being opened and closed by the piston, an inlet port for the opposite end of the engine cylinder and an inlet port for the metallic path having timed communication with a down draft carburetor.

2. In an internal combustion engine, an initial 10 fresh charge compression chamber, a combustion chamber, a double headed piston separating said chambers, a fuel transfer cylinder, a booster piston arranged for reciprocatory movement within the fuel transfer cylinder, the periphery of the 15 piston being cylindrical in form and tubular at its upper end, an annular groove formed in the periphery of the piston below the upper tubular end thereof providing a fresh charge inlet and transfer passage communication from a source 20 of fresh charge supply to the fresh charge compression chamber, the wall of the upper tubular end of said piston having a cutaway portion providing an outlet passage communication from the initial fresh charge compression chamber to the 25 fuel transfer cylinder and said piston adapted to boost the initially compressed fresh charge delivered to the fuel transfer cylinder from the compression chamber, into the combustion chamber to be again compressed and fired at the end of the 30 outward stroke of the engine cylinder piston and the combustion chamber having an exhaust port for the discharge of the burnt gases at the end of the inward stroke of the engine cylinder piston which inward stroke of the piston compresses a 35 fresh charge in the compression chamber simultaneously with the boosting of a compressed charge from the fuel transfer cylinder into the combustion chamber.

3. In an intake manifold for internal combustion engines of the two cycle type, a piston valve 40 for reciprocatory movement in the manifold, said valve having an annular groove providing a fresh charge passage communication from a source of fresh charge supply to an initial compression chamber, the upper end of said valve being tubular and having a cutaway wall portion 45 to provide a compressed charge passage communication from the compression chamber to the intake manifold above the piston valve to be boosted by the piston valve into the combustion 50 chamber of the engine wherein it is recompressed and then fired at the end of the upstroke of the piston of the engine and from which combustion chamber the burnt gases are discharged at the instroke of the piston approximately simultaneously with the boosting of an initially compressed fresh charge from the manifold.

4. In an intake manifold for internal combustion engines of the two cycle type, a cylinder, a double headed piston for reciprocatory movement in the cylinder and forming an initial 60 fresh charge compression chamber at one end and a combustion chamber at the opposite end thereof, an inlet manifold member having a fresh charge passage, a piston valve for reciprocatory movement in the manifold passage, said valve having an annular groove providing a fresh charge passage communication from a source of fresh charge supply to an initial compression chamber, the upper end of said valve being tubular and having a cutaway wall portion to provide a compressed charge passage communication from the compression chamber to the intake manifold above the piston valve to be boosted by 65 the piston valve into the combustion chamber.

of the engine wherein it is recompressed and then fired at the end of the upstroke of the piston of the engine and from which combustion chamber the burnt gases are discharged at the instroke of the piston approximately simultaneously with the boosting of an initially compressed fresh charge from the manifold.

5. In a two cycle internal combustion engine, the combination with the cylinder and the crank shaft thereof, of a double headed piston arranged for reciprocation in the cylinder and to provide a compression chamber in the lower end of the cylinder and a recompression and combustion chamber in the upper end of the cylinder, two connections between the piston and the crank 10 of the crankshaft, there being a gaseous fuel admission and discharge port formed in the wall of the compression chamber at the clearance part of the compression chamber, an intake manifold integral with the cylinder having a bored chamber and arranged on one side of the cylinder, there being a compressed gaseous fuel admission port in the wall of the recompression and combustion chamber of the cylinder communicating with the upper end of the intake manifold chamber, there being an exhaust port in said combustion chamber, said admission and exhaust ports being controlled by the piston, reciprocating means in the intake manifold chamber, means for admitting gaseous fuel from a source of supply to the compression chamber and also admitting the compressed gaseous fuel from the compression chamber to the intake manifold and said reciprocating means acting as a booster for delivering the compressed gaseous fuel in the 20 intake manifold into the recompression and combustion chamber.

6. In a two stroke cycle internal combustion engine, the combination with an engine cylinder and a double headed piston working therein, 40 of a head fitted with rings in the lower end of said engine cylinder, means for changing the position of the head within the cylinder, a fuel transfer cylinder associated with the cylinder, fuel ports communicating at opposite ends of 45 the engine cylinder with the fuel transfer cylinder and means mounted in the fuel transfer cylinder for boosting a charge from the transfer cylinder into one end of the engine cylinder.

7. In a two stroke cycle internal combustion engine, the combination with an engine cylinder having a double headed piston therein to provide a working cylinder at the upper end thereof of having an inlet port and an exhaust port, of a fuel compressing cylinder formed at the lower 50 end thereof having a combined fuel inlet and outlet port, a head fitted with rings adjustably mounted within the lower end of the fuel compressing cylinder, a fuel transfer cylinder disposed alongside the engine cylinder and means 55 for controlling the combined fuel inlet and outlet port of the fuel compressing cylinder.

8. In a two stroke cycle internal combustion engine, the combination with an engine cylinder having a double headed piston therein to provide a working cylinder at the upper end thereof of having an inlet port and an exhaust port, of a fuel compressing cylinder formed at the lower 60 end thereof having a combined fuel inlet and outlet port, a head fitted with rings adjustably mounted within the lower end of the fuel compressing cylinder, a fuel transfer cylinder disposed alongside the engine cylinder, means 65 for controlling the combined fuel inlet and outlet port of the fuel compressing cylinder and a 70

75

plunger within the transfer cylinder to boost a charge therefrom into the working cylinder.

9. In a two stroke cycle internal combustion engine, the combination with an engine cylinder having a charge inlet port and an exhaust port and having a double headed piston working therein controlling said ports and providing for a working cylinder at the upper end of the cylinder and a fuel compressing cylinder at the lower end thereof, means for varying the fuel compression space within the compressing cylinder, means for admitting fuel thereto to be compressed, a fuel transfer cylinder, means for admitting a compressed charge into the transfer cylinder from the compressing cylinder and means for boosting a compressed charge from the transfer cylinder into the working cylinder to be fired after it has again been compressed in the working cylinder.

20 10. In a two stroke cycle internal combustion engine, the combination with an engine cylinder having a charge inlet port and an exhaust port and having a double headed piston working therein controlling said ports and providing for a working cylinder at the upper end of the cylinder and a fuel compressing cylinder at the lower end thereof, means for varying the fuel compression space within the compressing cylinder, means for admitting fuel thereto to be compressed, a fuel transfer cylinder, means for admitting a compressed charge into the transfer cylinder from the compressing cylinder, means for boosting a compressed charge from the transfer cylinder into the working cylinder to be fired after it has again been compressed in the working cylinder and means for inducting air into the compressing cylinder near the end of the up-stroke of the piston within the engine cylinder.

11. In combination with an engine cylinder having a working portion and a pumping portion, of a double headed piston workable in said cylinder, a head fitted with rings mounted in the lower end of the pumping portion of the engine cylinder, means for moving the position of the head in the lower end of the pumping cylinder to change the area thereof, the wall of the pumping portion of the engine cylinder having a port therein serving both as a fuel inlet and outlet port.

50 12. In combination with an engine cylinder having a working portion and a pumping portion, of a double headed piston workable in said cylinder, a head fitted with rings mounted in the lower end of the pumping portion of the engine cylinder, means for moving the position of the head in the lower end of the pumping cylinder to change the area thereof, the wall of the pumping portion of the engine cylinder having a port therein serving both as a fuel inlet and outlet port, and said engine cylinder wall also having an auxiliary port therein disposed at a higher elevation than the fuel port serving as an air inlet to the pumping end of the cylinder for admitting air thereto after having induced a fuel charge thereto.

13. In combination with an engine cylinder having a working portion and a pumping portion, of a double headed piston workable in said cylinder, a head fitted with rings mounted in the lower end of the pumping portion of the engine cylinder, means for moving the position of the head in the lower end of the pumping cylinder to change the area thereof, a fuel transfer cylinder integral with the engine cylinder, port communications between the lower end of the pumping

cylinder and transfer cylinder, port communication between the transfer cylinder and the working cylinder, the latter port communication controllable by the double headed piston, means mounted in the transfer cylinder controlling the port communication between the pumping cylinder and the transfer cylinder and means for boosting a charge admitted from the pumping cylinder to the working cylinder for inducing it into the working cylinder.

14. In combination with an engine cylinder having a working portion and a pumping portion, of a double headed piston workable in said cylinder, a head fitted with rings mounted in the lower end of the pumping portion of the engine cylinder, means for moving the position of the head in the lower end of the pumping cylinder to change the area thereof, a fuel transfer cylinder integral with the engine cylinder, port communications between the lower end of the pumping cylinder and transfer cylinder, port communication between the transfer cylinder and the working cylinder, the latter port communication controllable by the double headed piston, means mounted in the transfer cylinder controlling the port communication between the pumping cylinder and the transfer cylinder, means for boosting a charge admitted from the pumping cylinder to the working cylinder for inducing it into the working cylinder and a pair of spark plugs carried by the head of the engine cylinder for alternate firing of the charge delivered to the working cylinder from the transfer cylinder.

15. In combination with an engine cylinder divided into a working cylinder and a fuel pumping cylinder by the employment of a double headed piston reciprocally mounted therein, means for changing the area of the pumping cylinder, a fuel transfer cylinder, means for admitting fuel into the pumping cylinder to be compressed therein, means for admitting the compressed fuel from the pumping cylinder into the transfer cylinder, means for boosting the compressed charge in the transfer cylinder into the working cylinder and therein to be again compressed by the double headed piston.

16. In combination with an engine cylinder divided into a working cylinder and a fuel pumping cylinder by the employment of a double headed piston reciprocally mounted therein, means for changing the area of the pumping cylinder, a fuel transfer cylinder, means for admitting fuel into the pumping cylinder to be compressed therein, means for admitting the compressed fuel from the pumping cylinder into the transfer cylinder, means for boosting the compressed charge in the transfer cylinder into the working cylinder and therein to be again compressed by the double headed piston, and two spark plugs carried by the head of the engine cylinder at the working end thereof, said spark plugs adapted to be fired alternately for igniting alternate charges in the working cylinder.

17. In an internal combustion engine of the class described, an engine cylinder, a double headed piston reciprocally mounted in the engine cylinder and dividing the cylinder into a working cylinder at one end and a fuel pumping cylinder at the opposite end, the wall of said working cylinder having an exhaust port therein, an inlet port in the working head end of the piston, a fuel transfer cylinder disposed in parallel relation with the engine cylinder, a port in communication with the pumping cylinder and

- the transfer cylinder, an outlet port in the transfer cylinder with which the port of the piston registers at the end of the down stroke thereof, a piston workable within the transfer cylinder and controlling the port of the pumping cylinder, said piston acting as a booster to discharge compressed fuel from the transfer cylinder to the working cylinder wherein the compressed fuel is recompressed and means for firing the charge in the working cylinder, said means including two spark plugs which fire alternately.
18. In an internal combustion engine of the class described, a working cylinder, a fuel pumping cylinder integral therewith, a double headed piston working in said cylinders, a fuel transfer cylinder integral with the working and pumping cylinders, a piston valve working in said transfer cylinder, means for admitting a charge from a source of supply to the pumping cylinder, means for admitting the charge from the pumping cylinder to the transfer cylinder under pressure, means for discharging the compressed charge from the transfer cylinder to the working cylinder wherein it is recompressed before it is fired and means for firing the charge in the working cylinder.
19. In an internal combustion engine of the class described, a working cylinder, a fuel pumping cylinder integral therewith, a double headed piston working in said cylinders, means within the pumping cylinder whereby the area thereof can be changed, a fuel transfer cylinder integral with the working and pumping cylinders, a piston valve working in said transfer cylinder, means for admitting a charge from a source of supply to the pumping cylinder, means for admitting the charge from the pumping cylinder to the transfer cylinder under pressure, means for discharging the compressed charge from the transfer cylinder to the working cylinder where-

in it is recompressed before it is fired and means for firing the charge in the working cylinder.

20. In an internal combustion engine of the class described, a working cylinder, a fuel pumping cylinder integral therewith, a double headed piston working in said cylinders, a head fitted with rings disposed in the lower end of the pumping cylinder, means for raising and lowering the position of the head in the pumping cylinder, a fuel transfer cylinder integral with the working and pumping cylinders, a piston valve working in said transfer cylinder, means for admitting a charge from a source of supply to the pumping cylinder, means for admitting the charge from the pumping cylinder to the transfer cylinder under pressure, means for discharging the compressed charge from the transfer cylinder to the working cylinder wherein it is recompressed before it is fired and means for firing the charge in the working cylinder.

21. In combination with an engine cylinder having an inlet port and an outlet port, of a double headed piston in said cylinder forming the cylinder into a working cylinder and fuel pumping cylinder and said piston controlling said inlet and exhaust ports, a head in the pumping cylinder, means for movably supporting said head, a fuel transfer cylinder, a port connection between the compression clearance end of the pumping cylinder and the fuel transfer cylinder, means permitting the introducing of a fuel charge from a source of supply into the pumping cylinder wherein it is compressed, means for permitting the compressed charge to be introduced into the transfer cylinder and means for boosting the compressed charge in the transfer cylinder into the working cylinder wherein it is recompressed and means for firing the charge in the working chamber.

GEORGE L. STREBLER. 40
